Primary Examiner — Mary Ann Calabrese*Assistant Examiner* — Catherine Ho(74) Attorney, Agent, or Firm — Leanne Taveggia Farrell; Westman, Champlin & Koehler, P.A.(57) CLAIM

The ornamental design for a display table, as shown and described.

DESCRIPTION

FIG. 1 is a front perspective view of a display table showing our new design;

FIG. 2 is a back perspective view thereof;

FIG. 3 is a front view thereof, the back view being identical;

FIG. 4 is a right side view thereof, the left side view being identical; and,

FIG. 5 is a top view thereof.

The broken lines shown in the drawings are included for purposes of illustrating portions of the display table and form no part of the claimed design.
